O. G. RUST.
SUSPENDER END.
APPLICATION FILED DEC. 23, 1908.

1,079,726.

Patented Nov. 25, 1913.

UNITED STATES PATENT OFFICE.

ORTON G. RUST, OF SPRINGFIELD, OHIO.

SUSPENDER-END.

1,079,726.

Specification of Letters Patent. Patented Nov. 25, 1913.

Application filed December 23, 1908. Serial No. 468,968.

To all whom it may concern:

Be it known that I, ORTON G. RUST, a citizen of the United States, residing at Springfield, in the county of Clark and State 5 of Ohio, have invented certain new and useful Improvements in Suspender-Ends, of which the following is a specification, reference being had therein to the accompanying drawings.

- 10 This invention relates to suspender-ends. The object of the invention is to provide a suspender-end in which each of the button-straps will be formed of a separate piece of material, but which, in the assembled device, will have both the appearance and strength of a suspender-end in which the two button-straps are formed of the same piece of material; further, to provide a single means for connecting together the 15 adjacent ends of the two buttons-straps and for connecting said straps to the cast-off; to provide a cast-off adapted to fold about the adjacent ends of the button-straps; to provide a common means for connecting together the 20 adjacent ends of the two button-straps, for connecting the button-straps to the cast-off and for connecting the folded over portion of the cast-off to the body portion thereof; to provide a cast-off having its reinforcing strip 25 formed integral therewith and adapted to be folded about the adjacent ends of the button-straps; and further, to provide an auxiliary support which will be secured to the cast-off by the same means by which the 30 button-straps are secured thereto.

With these objects in view my invention consists in certain novel features and in certain combinations and arrangements of parts hereinafter to be described, and then 40 more particularly pointed out in the claims.

In the accompanying drawings, Figure 1 is a front elevation of a device embodying my invention; Fig. 2 is a sectional view, taken on the line $x-x$ of Fig. 1; Fig. 3 is 45 a detail view of a slightly modified form of cast-off; Figs. 4 and 5 show slightly modified arrangements of the button-straps; Fig. 6 is a sectional view, showing a slightly modified form of the invention, and Fig. 7 is 50 a complete sectional view including the construction shown in Fig. 3.

In Figs. 1 and 2 of these drawings I have shown one embodiment of my invention and have shown the suspender-end 1 as comprising 55 two button-straps 2, each of which is formed of a separate piece of material.

These straps have their outer ends flat to receive the buttonholes 3 and are folded upon themselves for a portion of their length, as shown at 4, to form a cord-like structure. This folded portion of the button-strap preferably begins at a point slightly beyond the inner end of the button-hole and extends, in the form shown in Figs. 1 and 2, to a point near the inner end of the button-strap, the inner end being flat. The flat inner ends of the button straps overlap and are connected one to the other and are secured to the cast-off 5 in any suitable manner, the same means being preferably employed to connect together the overlapping ends of the button-straps and to connect the button-straps to the cast-off. In the present instance, the cast-off 5 comprises a flexible loop of leather having one end folded about 60 the adjacent ends of the button-straps, as shown at 6, and secured to the body portion of the cast-off, a single connecting means being preferably employed for connecting together the adjacent ends of the button-straps, for connecting the button-straps to the cast-off and for connecting the folded over portion of the cast-off to the body portion thereof. This connecting means 65 is preferably employed for connecting together the adjacent ends of the button-straps, for connecting the button-straps to the cast-off and for connecting the folded over portion of the cast-off to the body portion thereof. This connecting means 70 preferably comprises one member, 7, of a head-and-socket fastening device, the other member, 8, of which is connected to the other end of the loop forming the cast-off 5. This end of the cast-off is adapted to be extended through a connecting member 9 75 carried by the suspender-strap 10, after which the two members of the fastening device are connected together, thereby securing the suspender-end to the suspender-strap. Thus it will be apparent that the 80 overlapped adjacent ends of the two button-straps are entirely concealed within the folded over portion of the cast-off, thereby giving the two button-straps the appearance 85 of being formed from an integral piece of material; further, that the manner of connecting the two button-straps together and securing the same to the cast-off is such as to give the same a large degree of strength, thus causing the suspender-end comprising 90 the two separate straps to resemble, both in appearance and in strength, the suspender-end comprising integral button straps. In addition to connecting together the overlapping ends of the button-straps, securing the 95 button-straps to the cast-off and securing the overlapping portion of the cast-off to 100 the body portion of the cast-off, the connecting member 9 is adapted to be secured to the body portion of the cast-off, thereby securing the suspender-end to the body portion of the cast-off. In addition to connecting together the overlapping ends of the button-straps, securing the button-straps to the cast-off and securing the overlapping portion of the cast-off to 105 the body portion of the cast-off, the connecting member 9 is adapted to be secured to the body portion of the cast-off, thereby securing the suspender-end to the body portion of the cast-off. In addition to connecting together the overlapping ends of the button-straps, securing the button-straps to the cast-off and securing the overlapping portion of the cast-off to 110 the body portion of the cast-off, the connecting member 9 is adapted to be secured to the body portion of the cast-off, thereby securing the suspender-end to the body portion of the cast-off.

the body portion thereof the member 7 of the fastening device also serves to connect to the cast-off one end of a reinforcing strip 11, the other end of which is secured to the cast-off by the other member 8 of the fastening device.

While I have shown, in Figs. 1 and 2, and have above described one embodiment of my invention, it will be obvious that many alterations could be made in the same without departing from the spirit of my invention. In Fig. 3 of the drawings I have shown the cast-off 5 as having a reinforcing strip 12 formed integral with one end thereof. Thus, the reinforcing strip is folded about the adjacent ends of the button-straps together with the end of the cast-off and is then secured to the cast-off by the two members of the fastening device in substantially the same manner as above described. When the cast-off shown in Fig. 3 is folded into the shape shown in Fig. 7 the reinforcing strip 12 will extend from the end of the folded-over portion, instead of being fastened to the rear of the body portion in the rear of the button straps as shown in Fig. 2.

In Fig. 4 of the drawings I have shown the button-straps 2 as having their folded portions 4 extending to the inner ends thereof and as having these inner ends abutting instead of overlapping. The ends are secured together by suitable fastening devices, which, in the present instance, consists of a toothed clip 13 adapted to be clamped upon the adjacent ends of the two button-straps, thus securing the same firmly together. The end of the cast-off 5 is folded about the adjacent ends of the button-straps and the fastening device 13 and is secured to the body portion of the cast-off at a point immediately above the fastening device 13, thus securing the suspender-end to the cast-off and concealing from view the joint connecting the two button-straps.

In Fig. 5 I have shown an arrangement somewhat similar to that shown in Fig. 4, but have shown the adjacent ends of the two button-straps as secured together by a clip 14 having the form of a double pointed tack, the points of which are driven through the adjacent ends of the button-straps and clenched. The button-straps are then secured to the cast-off in the same manner as in Fig. 4.

In Fig. 6 I have shown a form of the device substantially similar to that shown in Figs. 1 and 2, but provided with an auxiliary supporting strap 15 which is secured at its upper end to the cast-off and is provided at its lower end with a suitable clasp or garment supporter. This auxiliary strap may be secured to the cast-off in any suitable manner, preferably by extending the fastening device 7, by means of which the button-straps are secured to the cast-off, through

the auxiliary strap, and, in the present instance, I have shown this strap as forming a continuation of the reinforcing strip 11 of the cast-off and extending through an aperture 16 in that portion of the cast-off which extends about the button-straps, but, obviously, the strap could be formed separately from the reinforcing strip if such a construction should be desirable.

Thus, it will be seen that my invention is capable, not only of wide modification, but also of combination with numerous other elements, all of which combine to produce a suspender-end which is capable of being manufactured from small pieces of material or leather scraps, and which, in its completed condition, has the same strength and the same finished appearance of the suspender-end in which the connected parts are formed of a single piece of material, the points of connection, in each instance, being concealed by the folded over portion of the cast-off.

While I have shown and described certain modifications of my invention it will be obvious that it is capable of still further modification, and, I, therefore, wish it to be understood that I do not desire to be limited to the details of construction shown and described, except as defined by the scope of the appended claims, for obvious modifications will occur to a person skilled in the art.

Having thus fully described my invention, what I claim as new and desire to secure by Letters Patent, is:—

1. In a suspender-end, a flexible cast-off comprising a body portion having its lower end folded upon itself, two button straps flexible throughout their length and each folded upon itself for a portion of its length, said button straps having their adjacent ends overlapping and connected one to the other within the folded-over lower end of said body portion, and a fastening device to connect said folded-over lower end to said body portion and to retain the connected ends of said button-straps within the folded-over lower end of said body portion, said body portion also having its upper end portion bent downward in front of the folded-over lower end portion thereof, connected to said body portion and serving both to connect the cast-off to the suspender and to conceal from view the upturned lower end and its fastening device.

2. In a suspender-end, the combination, with a cast-off comprising a body portion having its lower end folded upon itself and its upper end bent downward and arranged to extend in front of the folded-over lower end thereof, and two button-straps flexible throughout their length and having their adjacent ends secured within the folded-over lower end of said body portion, of a reinforcing strip secured to the folded-over

lower end of said body portion, extending along the inner surfaces of said body portion and said upper end portion and having its outer end secured to said upper end portion at a point removed from said body portion.

3. In a suspender end, the combination, with a cast-off comprising a body portion having its lower end folded upon itself and 10 its upper end bent downward and arranged to extend in front of the folded-over lower end of said body portion, and two button-straps flexible throughout their length and having their adjacent ends overlapping and 15 arranged within the folded-over lower end of said body portion, of an auxiliary supporting-strap having one end arranged between said body portion and the folded-over lower end thereof, and a single fastening 20 device for securing together the adjacent ends of said button-straps, for securing said button-straps to said body portion and for

securing said auxiliary supporting strap to said body portion.

4. In a suspender-end, the combination, 25 with two button-straps having flat outer ends, each strap being folded upon itself for a portion of its length, of a cast-off having one end folded about the adjacent ends of said button-straps, a reinforcing strip for 30 said cast-off having one end secured to said cast-off at a point removed from said folded over portion thereof, said reinforcing strip having an extension extending through that portion of said cast-off which is folded about 35 said button-straps, and means for securing said button straps to said cast-off and for securing said reinforcing strip to said cast-off.

In testimony whereof, I affix my signature in presence of two witnesses.

ORTON G. RUST.
